UNITED STATES PATENT OFFICE.

GEORGE A. LEIGHTON, OF ROSLINDALE, MASSACHUSETTS, ASSIGNOR TO AMERICAN CAN COMPANY, OF NEW YORK, N. Y., A CORPORATION OF NEW JERSEY.

DEVICE FOR REMOVING FRICTION PLUGS FROM CONTAINERS.

Application filed April 16, 1926. Serial No. 102,380.

This invention relates broadly to a device for opening cans and more specifically it has for its object the provision of an apparatus for removing the closure member of so called 5 friction plug cans.

In the manufacture of friction plug cans of the larger type, especially of the gallon and five gallon sizes, which are used for packing fish and similar bulky products, it is the 10 custom to finish both can body and friction closure or cover and assemble them in the can making factory before shipping them out to the customer. By this method it is certain that a plug will be supplied for every 15 can. This requires the customer to remove the friction closure from the empty can before filling the can. This removal of the friction closure has prior to my invention been done entirely by hand and a number of 20 people were required to remove the friction plugs to prepare the empty cans for the filling operation.

One of the objects of my invention resides in providing a simple apparatus for quickly 25 and easily removing the friction plugs from cans in a most economical manner whereby the employment of labor for doing this by hand is not further required.

Another object of my invention resides in 30 providing a device for removing friction plugs from cans, which device is constructed and arranged to firmly hold the assembled can body and plug while forcing them apart and without damage thereto.

Still another object of my invention resides 35 in a simple type of apparatus for removing friction plugs from cans which embodies a single hand control and also a conveniently disposed foot control, one of which controls 40 functions as a means for firmly holding the can and assembled plug and the other of which controls functions as a means for forcing the can body and plug apart.

Other objects and advantages of the invention 45 will be apparent as it is better understood from the following description, which taken in connection with the accompanying drawings discloses a further embodiment thereof.

Referring now to the drawings which form 50 part of this specification and in which like reference characters indicate corresponding parts,

Figure 1 is a front elevation of the apparatus, parts being broken away and showing

the device before a friction top can has been placed therein for removal of the friction plug.

Figure 2 is a longitudinal sectional view of the apparatus taken approximately along the 60 central vertical line, showing the opening lever in raised or inoperative position.

Figure 3 is a similar view to Figure 2 showing the opening lever in lowered operative or removing position and showing the foot 65 lever in depressed position.

Figure 4 is a cross sectional view taken along lines 4-4 of Figure 1.

The preferred form of my apparatus as illustrated in the drawings, comprises a preferably L-shaped metallic frame 10 secured to a suitable support 11 as by means of bolts 12. This frame rigidly supports a holding mandrel or chuck 13 of a cross section similar to the cross section of the recessed portion of 75 the friction plug to be removed from the can. In the present instance this chuck 13 is of circular conformation and of a diameter equal to the inner diameter of the recessed part of the friction plug 14. This chuck 13 is provided with ears 13' which are rigidly connected to the L-shaped frame 10 whereby the chuck is rigidly supported substantially at two opposed peripheral portions. A sliding plate 15 is reciprocably held between the vertical leg of the L-shaped frame 10 and the holding mandrel 13, a suitable groove being formed in the face of the mandrel 13 to provide a guideway. This plate 15 is normally held in raised position by means of a spring 80 16. Plate 15 can be lowered against the tension of this spring 16 by means of a pedal 17 pivoted at 18 and connected with the sliding plate by means of a connecting rod 19 in turn pivotally connected to the pedal at 20 and to 85 the sliding plate at 21. The upward and downward reciprocation of the sliding plate is limited by a stop screw 22 travelling in a slot 23 in the vertical shank of the L-shaped frame 10. This screw 22 has secured to its 90 apertured free end the lower end of spring 16 and the other extremity of said spring is secured to a perforated ring bolt 24 extending through the upper end of a frame extension 25 carried by the upper end of frame 10. 100

The upper end of plate 15 is constructed and arranged to provide a complementary chuck member adapted to cooperate with the mandrel 13 for firmly gripping the friction plug during the disassembling or prying off 110

operation. In addition it is constructed and arranged to provide a means for preliminarily wedging apart the friction plug and the can body. To this end the upper end of plate 15 is provided with a wedging and chucking element 26 which is shaped to conform to one-half of the exterior shape of the friction plug. In the present instance, since the friction plug is round this element is in the form of a half circle.

In addition there is provided means finally for completing the prying apart operation of the friction plug and can body. In the preferred form this is provided in the construction of an L-shaped lever 27 pivoted as at 28 to a bracket 29 bolted to the upper end of the plate 15 preferably through the wedge shaped element 26. This lever 27 is provided with a handle 29 and with a spring 30 which connects to the eye-bolt 24. This lever 27 is provided with a dog 33 pivoted thereto as at 31 and provided with an extension 36 engaging the under side of the lever 27. It will be noted that this dog is provided with bifurcations by which it is pivoted to the lever. This dog is arranged at such an angle to a positioned can body C that when the lever 27 is lowered from position shown in Figure 2 to that shown in Figure 3 the dog will engage the projecting bottom seam of the can body C and will pry off the latter from the friction plug 14 which is retained on the chuck 13. The extension 36 integral with the dog restricts the backward movement of the dog to the limit shown in Figures 2 and 3.

In operating my device a friction can body with its friction plug assembled thereto is positioned upon the stationary holding chuck 13 so that the chuck is forced into the recess of the friction closure and engages the inside walls of the said friction closure. The foot treadle 17 is then depressed which has the effect of lowering the sliding plate and the half circle wedge member 26 attached thereto. The sharp knife edge of said wedge member then enters between the curled top edge of the container body and the outwardly turned flange of the friction plug and pries them apart to the extent of the thickness of the wedge point or edge and at the same time secures the plug cover to the chuck. Simultaneously the lever 27 is grasped by the operator at the handle 29 and depressed to position illustrated in Figure 3, which operation causes the dog 33 to first engage the bottom seam flange and then pry off the container body from the friction closure which action was started by the wedge member 26. It will be seen that the knife edge of the wedge 26 also performs the important function of holding the friction plug upon the mandrel by tightly embracing it around at least one half of its periphery. After the container body has been completely pulled away from its friction plug the foot treadle 17 is released

and the slide and wedge member begin to rise back to inoperative position under the tension of the spring 16. The spring 30 will also return the lever 27 to inoperative position as soon as the operator releases the handle 29.

From the foregoing description it will be readily apparent that I have invented a very simple, compact, sturdy and yet inexpensive device which performs the removal of friction plugs from empty friction containers efficiently, economically and with much greater speed and less effort than has heretofore been possible.

It is thought that the invention and many of its attendant advantages will be understood from the foregoing description and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A device of the class described comprising a support, a mandrel mounted thereon and shaped to support a friction plug with the can body assembled thereto, means for preliminarily wedging apart said plug and can body, said means being constructed and arranged to grip the friction plug, and additional means for forcing said can body from said friction plug while the latter is gripped.

2. In a device of the class described the combination of a support, a mandrel thereon adapted to fit within a friction plug with the can body assembled thereto, means for gripping the outer periphery of said plug, and means for pressing the can body away from said plug.

3. In a device of the class described the combination of a support, complementary chuck members thereon for gripping the top and under side of the flange of a friction plug with the can body assembled thereto, and means for pressing the can body away from the friction plug while the latter is being held.

4. In a device of the class described the combination of a support, a mandrel inserted within a friction plug with the can body assembled thereto to support the same, a combined chucking and wedging member movable relative to said plug and adapted to wedge between the walls of said plug and the assembled can body and to engage the plug to hold the latter, and means for forcing the can body from said held plug.

5. A device of the class described comprising in combination a support, a circular mandrel adapted to be inserted within the recess of a friction plug with the can body assembled thereto, a member movable toward and from said mandrel and comprising an

arcuate wedge like surface adapted to be moved between the plug and the can body to pry the same apart and to permit the arcuate member to grip the plug, and means carried by said member for forcing the can body from the plug.

6. A device of the class described comprising in combination a support, a mandrel mounted thereon adapted to be inserted in the recess of a friction plug with the can body assembled thereto, a combined chucking and wedging member mounted on said support and movable toward and from said mandrel, said member having a surface constructed and arranged to wedge apart the can body and plug and to thereafter grip said plug, a lever mounted on said member and provided with means adapted to engage said can body to force the latter from the plug while the plug is gripped.

7. A device of the class described comprising in combination a support, a mandrel rigidly mounted thereon and adapted to fit within the recess of a friction plug with the can body assembled thereto, a plate slidably mounted between the mandrel and support, a pedal connected to and operating said plate, a spring for operating said plate in an oppo-

site direction to that of the pedal, a combined wedging and gripping member mounted on said plate and constructed and arranged to wedge between the beads of said plug and can body, an L-shaped lever pivotally mounted on said wedging member, said L-shaped lever having a dog pivotally mounted thereon and depending therefrom so as to engage the bottom bead of the can body to force the latter from the friction plug.

8. A device of the class described comprising in combination a support, a mandrel for holding a friction plug with the can body assembled thereto, a combined gripping and wedging member mounted on said support for initially wedging the can body apart from the plug and for thereafter gripping the plug, a pedal for operating the plate and a hand lever carried by said wedging member and having means for engaging the bottom bead of the can body for prying it from the plug.

9. In a device of the class described the combination of a support, a mandrel thereon for engaging a friction plug with the can body assembled thereto, and manually operable means for gripping the plug and for prying the can body therefrom.

GEORGE A. LEIGHTON.
